UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed March 11, 1927. Serial No. 174,452.

This invention relates to devices for holding cards or other stiff work-pieces in position on a cylindrical platen.

Heretofore, cards being inserted would frequently strike against the upper edge of the card-holder due to the difficulty in readily locating the opening of restricted area. It is therefore necessary, in many cases, for the operator to hunt and feel around until the card is properly guided into the holder. An object of my invention is to provide means for facilitating the insertion of cards; and to attain that result I have provided a groove in the platen at the opening to the card-holder, thus considerably enlarging the opening for the insertion of the card.

When typing on a card having a series of columns printed thereon, it is desired that the typing be properly spaced within the columns. This is especially important in columns which are just wide enough to receive one typed letter or numeral. To overcome this difficulty, a side-edge gage is provided, which is adjustably mounted on the platen, thereby enabling the card to be positioned accurately.

Other features and advantages will hereinafter appear.

In the accompanying drawings,

Figure 1 is a perspective view of my card-holder mounted in operative position on a platen.

Figure 2 is a perspective view showing details of the adjustable gage and the card-holder.

Figure 3 is a side view showing an inserted card in position to be typed upon.

Figure 4 is a side view showing a card being inserted in the card-holder.

Referring to Figure 1, my card-holder, consisting of an arcuate metal plate 1, is shown fixed on the platen 6 of a typewriting machine by means of screws 2, the heads of the screws flush with the outer surface of the plate 1. The plate 1 is concentric with the platen 6, and is undercut on the upper inner side, thus providing a space between the plate and the platen, and also a ledge 9, upon which the inserted card may rest. The platen 6 is gouged out near the upper edge of plate 1 to form a peripheral groove 3, which extends longitudinally of the platen and is parallel to the upper edge 11 of the plate 1. It will be seen that the groove 3 provides an enlarged opening for the card-holder; and a card 10,

while being inserted, will not strike against the upper edge 11 of the card-holder, as frequently happens when inserting a card in the restricted opening ordinarily presented.

At an upper corner of the card-holder, I provide a gage 4, which is formed from a piece of metal of the same thickness as the metal plate of the card-holder, and undercut to match the undercut of the card-holder plate, thus providing a surface 7 upon which the undercut part of plate 1 rests, and a ledge 12 which rests upon the upper edge 11 of the plate 1, the undercut parts being proportioned so that the outermost surfaces of the gage and the card-holder plate will be flush.

The upper portion of the gage 4 has an elongated aperture 8 to receive the screws 5 for adjustably mounting the gage on the platen. The aperture 8 is countersunk so that the heads of screws 5 will be flush with the outer surface of the gage.

The upper edge of the gage and the lower edge of the card-holder strip are beveled to favor easy passage over the feed-rolls 13, 14.

In operation, the card 10 (see Figure 4), to be inserted in the card-holder, is moved downwardly with the lower edge against the platen until the groove 3 is reached, and the upper edge 11 of the plate 1 has been passed. The lower edge of the card is then moved forwardly until it contacts with the inner surface of plate 1, and is then moved downwardly until it rests upon the ledge 9. Simultaneously with the insertion of the card it may be laterally positioned by guiding an edge against the gage 4. The platen is then rotated rearwardly in order that the card may be gripped by the feed-rolls 13, 14; and to position the card for the first line of typing.

Should it be desired to type in a narrow column, such as column 15 (see Figure 1), which may be not greater than a letter-space in width, the gage 4 may be used, and if necessary it may be slightly adjusted on the platen, and the card laterally positioned thereby so that a typed letter or numeral will fall properly within the border lines of the narrow column. The gage enables the use of cards of different sizes which have a series of columns printed thereon. The columns are usually so proportioned that it is only necessary to adjust the gage for one column in order to properly position all of the columns on the card.

Variations may be resorted to within the scope of the invention, and portions of the improvements may be used without others.

Having thus described my invention, I

5 claim:

1. In a typewriting machine, the combination of a revoluble platen and a card-holder consisting of a metal plate curved to fit the platen and having the upper portion of its 10 inner surface cut out so as to provide a pocket for holding a card, the platen having a longitudinal groove opposite and parallel to the upper edge of the metal plate to facilitate the insertion of a card in the pocket, and a gage 15 adjustably mounted on said platen at an upper corner of said card-holder to laterally position the card being inserted.
2. In a typewriting machine, the combination with a revoluble platen and a card-holding device fixedly mounted on said platen, of a gage for laterally positioning cards, said gage consisting of a metal plate having a portion for engagement with the card-holder, and being provided with an aperture extending lengthwise of the gage to receive screws for mounting the gage on the platen for adjustment longitudinally of the card-holder.

3. In a typewriting machine, the combination with a revoluble platen and a card-holding device fixedly mounted on the platen, of a gage for laterally positioning cards, said gage consisting of a metal plate curved to fit the platen and having a portion overlapping a portion of the card-holder, and having an 35 elongated slot extending longitudinally of the platen to receive means for mounting the gage on the platen for adjustment longitudinally of the card-holder.

4. In a typewriting machine, the combination of a revoluble platen and a card-holding device mounted on said platen, said device consisting of a metal plate curved to fit the platen and having the upper portion of its inner surface undercut throughout its length 45 to provide a space between the plate and the platen, a ledge upon which an inserted card may rest, and a gage for positioning the card longitudinally of the card-holder adjacent one end of said undercut portion adjustably 50 mounted longitudinally thereof.

5. In a typewriting machine, the combina-

tion with a revoluble platen and a card-holding device mounted on said platen, of a gage for laterally positioning a card inserted in said card-holding device, said gage having an 65 elongated aperture extending longitudinally of the platen to receive means for adjustably mounting said gage on the platen.

6. In a typewriting machine, the combination with a revoluble platen having a card-holding device secured thereto consisting of a longitudinal metal plate curved to fit the platen and having an undercut portion for receiving and holding a card thereon, of a gage-device consisting of a metal plate having the same thickness and curvature as the card-holder, and an extending portion to match the undercut portion of the card-holding plate upon which said portion of the card-holding plate rests with the ledge 70 formed at the extension on the gage-plate resting on the upper edge of the card-holding plate, whereby the outermost surfaces of the gage and the card-holder will be flush, and means for retaining said gage in a fixed position on the platen with respect to the card-holder.

7. In a typewriting machine, the combination with a revoluble platen having a card-holding device secured thereto consisting of 80 a longitudinal metal plate curved to fit the platen and having an undercut portion for receiving and holding a card thereon, of a gage-device consisting of a metal plate having the same thickness and curvature as the 85 card-holder, and an extending portion to match the undercut portion of the card-holding plate upon which said portion of the card-holding plate rests with the ledge formed at the extension on the gage-plate resting on 90 the upper edge of the card-holding plate, whereby the outermost surfaces of the gage and the card-holder will be flush and the gage-device may be moved longitudinally along the card-holder for positioning a card in a longitudinally adjusted position with respect to the card-holder and the letter-space positions of the platen, and means for retaining said gage in a fixed adjusted position on the platen with respect to the card-holder.

ALFRED G. F. KUROWSKI.
